UNITED STATES PATENT OFFICE.

JAMES V. BREDLE, OF CEDAR RAPIDS, IOWA.

DESIGN FOR A WEEDEER-HEAD.

51,327.

Specification for Design.

Patented Oct. 9, 1917.

Application filed June 21, 1917. Serial No. 175,989. Term of patent 7 years.

To all whom it may concern:

Be it known that I, JAMES V. BREDLE, a citizen of the United States, residing at Cedar Rapids, in the county of Linn and State of Iowa, have invented a new, original, and ornamental Design for Weeder-Heads; and I do hereby declare the following to be a specification thereof, reference being had to the accompanying drawing, forming a part thereof.

The figure shown in the drawing is a view in perspective showing my new design for

a weeder head, as seen from a point diagonally opposite the handle and above the weeder head.

I claim:

The ornamental design for a weeder head, as shown.

In testimony whereof I affix my signature in presence of two witnesses.

JAMES V. BREDLE.

Witnesses:

E. W. WINTER,
CHAS. A. WINTER.
